UNITED STATES PATENT OFFICE

HENRY W. DIECK, OF BROOKLYN, NEW YORK, ASSIGNOR TO THE STANDARD TEXTILE PRODUCTS COMPANY, OF NEW YORK, N. Y., A CORPORATION OF OHIO

DESIGN FOR OILCLOTH

Application filed October 19, 1928. Serial No. 28,564. Term of patent 3½ years.

To all whom it may concern:

Be it known that I, HENRY W. DIECK, a citizen of the United States, residing in the borough of Brooklyn, county of Kings, and State of New York, have invented a new, original, and ornamental Design for Oil-cloth, of which the following is a specification, reference being had to the accompanying drawing, forming part thereof.

The figure of drawing is a view in top plan of a piece of oilcloth embodying my new and ornamental design, a complete repeat unit being comprised within the space enclosed by the dot and dash lines.

I claim:

The ornamental design for oilcloth, as shown and described.

HENRY W. DIECK.
